ENGINE AND TORQUE TRANSMITTER
CONTROL

Emil Grieshaber and William J. Johnson, Jr.,
Milwaukee, Wis., assignors to Nordberg Manufacturing Company, Milwaukee, Wis., a corporation of Wisconsin

Application December 27, 1943, Serial No. 515,867

3 Claims. (Cl. 192—01)

1

This invention relates to the control of internal combustion engines as used, for example, in ship propulsion.

It is common practice to connect two Diesel engines to a single propeller shaft, each engine driving a corresponding pinion which meshes with a large gear on the propeller shaft. Between each engine and its pinion is interposed a torque transmitter, which usually is Fottinger hydraulic drive, or an electric reaction drive. These drives damp out vibration, give controlled slip and provide for complete disconnection.

The primary control of the energy input of the engines is manual, but an overspeed governor has been considered essential, and it is not uncommon to use two governors per engine in order to secure full control.

The purposes of the present invention are (1) to provide a single governor which will act to limit speed at two different values, a low speed appropriate to idling or no-load conditions and a higher speed for operation under load; (2) to afford limited adjustment of the low speed setting, and ready manual adjustment over a wide range, of the higher speed-limiting setting, the two adjustments being wholly independent; (3) to provide a shifting mechanism indifferent to the two adjustments and serving to select between the two settings; and (4) to relate the shifting mechanism to the torque transmitter in such a way that failure or deenergization of the torque transmitter will set the governor of the corresponding engine for low speed.

Generally stated there is a shiftable seat for the speeder spring of the governor. This seat is biased toward a low speed stop by the speeder spring. The seat may be shifted in the other direction until arrested by an adjustable high speed stop, and such shift is effected by energizing a solenoid which stresses a loading spring heavy enough to move the speeder seat full stroke and hold it against the high speed stop in any adjusted position thereof, despite the reaction of the speeder spring. The solenoid is energized simultaneously with the energization of the corresponding torque transmitter, so that disconnection of the engine intentionally or by accident will set the governor to limit the engine to idling speed.

Thus the desirable characteristics of manual control are possible, using a single governor to limit engine speed automatically, and to values appropriate to load conditions.

In the accompanying drawings the invention is illustrated as embodied in a Woodward governor.

The resulting governor mechanism is not claimed herein but forms the subject matter of a divisional application Serial No. 565,689, filed November 29, 1944.

5 Figure 1 is a vertical axial section through the governor on the line 1—1 of Fig. 2.

Figure 2 is a similar section on the line 2—2 of Fig. 1.

Figure 3 is a diagrammatic plan showing how 10 the solenoid circuit of each of two governors is connected to the torque transmitter circuit of two engines with corresponding ones of which the respective governors are associated.

The Woodward governor chosen for illustration 15 is of a type in which the fuel limiting control mechanism of the related engine is actuated by a servomotor generally indicated in Figure 1 by the numeral 11.

The controlling element is a piston valve 12 20 which regulates admission and exhaust flows through ports in a valve seat 13. This seat rotates but does not move axially in the governor housing 14. The upper end of the rotating valve seat 13 carries a yoke 20 upon which the fly-ball carriers 15 are pivoted by means of annular ball bearings 16. The fly-ball carriers have inwardly projecting arms which react upwardly on the outer race 17 of a ball thrust bearing carried by the upper end of the stem of valve 12. The 25 stem 12 carries above the ball thrust bearing 17 a spring seat 18 upon which reacts the trumpet shaped speeder spring 19.

The parts so far described are of standard construction and function in their usual manner, 30 so that no elaborate description of details is essential. The significant thing so far as the present invention is concerned is the presence of a fly-ball governor or its equivalent having a speeder spring 19. One of the features of novelty 35 is the way in which the upper end of the speeder spring 19 is sustained.

Vertically guided in a guideway formed in bracket 21 sustained by the governor housing is a tube 22. Slidably within and guided by the 40 tube 22 is a spring seat 23 having a laterally extending stem 24 which works in a longitudinal motion-limiting slot 25 formed in the tube 22. Carried by a portion of the bracket 21 is an adjustable stop screw 26 which is in the path of the stem 24 and serves to limit the upward movement of the spring seat 23 in the tube 22. Stop screw 26 determines the idling or low speed adjustment of the speeder spring 19, and this adjustment is in effect when the stem 24 is in engagement with the lower end of the stop screw

26. This is a semi-permanent adjustment and consequently the stop screw 26 is locked by a check nut as shown. The lower end of the slot 25 serves as the stop which determines the downward limit of motion of the spring seat 23 and establishes a high-speed limiting adjustment of the stress on the speeder spring 19. Adjustment is made by sliding the tube vertically.

The illustrated means for effecting the adjustment comprises a pinion 27 which engages rack 10 teeth 28 formed on the tube 22. The pinion 27 may be rotated by a motion reducing gear train comprising the gears 29, 31, 32 and 33, the gear 33 being turned by a knob 34 which is accessible for manual adjustment. The arrangement is 15 clearly shown in Figure 2 of the drawings. By turning the knob 34 the operator moves the tube 22 vertically and thus changes the position of the lower end of the slot 25.

The speeder spring 19 biases spring seat 23 20 upward until arrested by the low speed stop 26. To establish the high speed adjustment the spring seat 23 must be urged downward with a force sufficient to overpower the reaction of the speeder spring 19. The range of such motion is variable, 25 being dependent on the adjustment of the sleeve 22. In order to accommodate the contemplated variations in the range of motion, the downward thrust is delivered through a coil compression spring 35. This reacts downward on a flange 30 on the lower end of a stem 36 which is in thrust engagement with the spring seat 23. At its upper end the spring 35 is seated against the upper end of a cuplike thrust member 37 which is slidably mounted on the tube 22, and has near its lower 35 end an encircling flange 38.

A lever 39 is fulcrumed at 41 in the governor housing and is forked at its righthand end to straddle the cup-shaped member 37 and engage the flange 38. The other end of the lever 39 is 40 connected by a link 42 with the movable core or armature 43 of a solenoid motor. When the solenoid motor is deenergized, the lever 39 swings counterclockwise, relieving the stress on the spring 35 so that the spring seat 23 moves to the upper or low speed position. When the motor is energized the lever 39 turns clockwise to the position illustrated in Fig. 1, stressing spring 35 sufficiently to hold the spring seat 23 in the lowest position permitted by the existing adjustment 50 of the sleeve 22, whatever that may be. At such times the stem 24 engages the lower end of the slot 25. The construction permits the actuating motor to move full stroke regardless of the existing adjustments.

Since the governor is to be controlled in relation to the torque transmitter and since the governor should shift to low-speed setting upon failure of any part of the system, it is desirable that the solenoid permit establishment of the 60 low-speed setting when the solenoid is deenergized. Consequently the solenoid is energized constantly under normal running conditions, a consideration which controls its design.

The solenoid motor has two windings 45 and 46 wound on a laminated core 47 and connected in series. An L-shaped lever 48 fulcrumed at 49 and biased clockwise (as seen in Fig. 1) by spring 51 carries a contactor 52 which is insulated from the lever 49 at 53. When the lever is allowed to 70 turn clockwise, it engages contacts 54 and 55 establishing a shunt path around winding 46 (see Fig. 3). This condition subsists until armature 43 nears its uppermost position, at which time a head 56 carried by the armature 43 strikes lever 75

48 and turns it counterclockwise to the position shown in Fig. 1.

In Fig. 3 two engines 61 and 62 are indicated as driving pinions 63 and 64 through torque transmitters 65 and 66, which are diagrammed as of the dynamo electric type shown for example in the patent to Sperry 1,682,358, granted August 28, 1928. Pinions 63 and 64 drive gear 67 on propeller shaft 68.

Assuming engines 61 and 62 are Diesel engines, engine 61 has a controller 71 and engine 62 a similar controller 72 connected respectively as indicated at 73 and 74 to the fuel controls of the engine. Each also operates a corresponding switch 75, 76 respectively controlling through relay switches 77, 78 the energizing circuits A and B of the torque transmitters 65, 66. The relay switch mechanisms 77 and 78 would include the usual protective devices (i. e. circuit breakers and the like) for the circuits which they control.

Associated with each engine 61, 62 is one of two governors of the type shown in Figs. 1 and 2. Each governor is driven by its own engine and limits the fuel feed of that engine through connections which are conventional and hence are not diagrammed in Fig. 3.

The windings 45, 46 of each governor are in circuits C and D related to circuits A and B respectively so as to be deenergized whenever the corresponding torque transmitter is deenergized and consequently uncoupled or inactive.

Considering the controller 71 and referring to the idling position in which it is shown, the torque transmitter 65 is deenergized by the opening of switch 75 as are the windings 45, 46 of the related governor which thus limits the speed of engine 61 to idling speed. Controller 72, however is shown set for low speed under load. Its switch 76 is closed. Thus the related torque transmitter 66 is energized to connect the engine 62 to its load, and windings 45, 46 of the governor driven by engine 62 are energized, setting the governor to impose the higher limit on the speed of engine 62.

The circuits are indicated only in the simplest diagram to disclose the principle, and the various protective devices used in commercial installations are omitted to avoid confusing the drawings.

It is sometimes necessary, for test or warm up and similar purposes, to operate an engine above idling speed but not under load. To permit this, the governor shown in Figs. 1 and 2 can be locked in high-speed setting. A counterbored plunger 81 with actuating knob 82 and bayonet-lock slot 83 is guided in the top of the governor housing. It is shown locked in its upper or inactive position. It may be moved down manually and locked in a position in which thrust member 87 is held fully depressed. At such time the governor imposes the higher speed limit.

In certain of the claims the term "torque transmitter of the dynamic reaction type" is used generically to include Föttinger torque converters (fluid drives), transmitters of the Sperry type and functionally similar devices characterized by speed differentials between driving and driven elements, and by the possibility of disconnection.

A preferred embodiment of the governor and one application thereof has been described in considerable detail, but merely to disclose the principles of the invention, the scope of which will be defined in the claims.

What is claimed is:

1. The combination of an engine; a governor

arranged to limit the energy input of said engine; motor means for setting said governor to establish different engine limit-speeds appropriate to idling conditions and loaded conditions of engine operation; torque transmitting means of the dynamic reaction type through which load is imposed on said engine; and means for energizing said torque transmitting means and said motor, so arranged that the governor is set for load conditions when the torque transmitting means is energized and for no load conditions at other times.

2. The combination of an engine; a governor arranged to limit the energy input of said engine; means shiftable to change the control point of said governor between a low speed setting for idling operation and a higher speed setting for operation under load; means biasing said shiftable means toward low speed setting; electric means serving when energized to shift said means to high speed setting; a torque transmitter of the dynamo-electric type for controlling the application of load to the engine; and means for energizing and deenergizing said electric means and said torque transmitter concurrently.

3. The combination of an engine; manually operable means for controlling said engine; a

speed limiting governor driven by and exercising a supervising control over said engine; shiftable means for setting said governor to impose a low idling speed limit on said engine and alternatively a higher operating speed limit on said engine; a torque transmitter of the dynamic reaction type through which said engine is loaded; and connections between said torque transmitter and said shiftable means serving to cause shift of the latter to its low speed setting when the torque transmitter is inactive and to the high speed setting when the torque transmitter is active.
